R. A. FILKINS, OF NORTH ADAMS, MASSACHUSETTS, ASSIGNOR TO HIMSELF AND W. B. WERDEN, OF WAUKEGAN, ILLINOIS.

Letters Patent No. 71,729, dated December 3, 1867.

IMPROVEMENT IN LOW-WATER INDICATORS.

The Schedule referred to in these Letters Patent and making part of the same.

TO ALL WHOM IT MAY CONCERN:

Be it known that I, R. A. FILKINS, of North Adams, Berkshire county, Massachusetts, have invented a new and improved Water-Indicator for Steam-Boilers; and I do hereby declare that the following is a full, clear, and exact description thereof, which will enable others skilled in the art to make and use the same, reference being had to the accompanying drawings, forming part of this specification, in which—

Figure 1 represents a vertical central section of my invention.

Figure 2 is a horizontal section of the same, the plane of section being indicated by the line *z z*, fig. 1.

Similar letters of reference indicate corresponding parts.

This invention relates to a device by which the height of the water in a steam-boiler can be instantly ascertained without the use of faucets or taps, and which, when the water in the boiler descends below a certain line, will blow an alarm-whistle, and notify the attendants of the fact.

A represents an upright cylinder, which is connected with a steam-boiler by means of two pipes, a siphon, *a*, near its bottom for conducting water, and a pipe, *b*, near its top for conducting steam from the boiler into the cylinder A. A pipe, *c*, connects the lower part of the cylinder A with an upright glass tube, B, which is held between two metal caps, *d d*. The lower cap *d* is screwed upon an elbow on the pipe *c*, and the upper cap *d* is screwed to the lower end of an upright tube, C, which is connected with the upper part of the cylinder A by a pipe, *e*, as is clearly shown in fig. 1. From the sides of the tube C, and from those of the upright portion of the pipe *e*, project three or more short bars, *f f* and *g g*, respectively; and the ends of the bars *f* are connected with those of the bars *g* by upright rods, *D D*. The latter form a protection for the glass tube, and serve to sustain the pipe C and its appendages. The glass tube B is surrounded by another glass tube, E, the ends of which are held between the caps *d d*. The object of the tube E is to prevent the cold air from striking the outside of the tube B while the hot water is on the inside of the same. The water in the boiler enters the cylinder A through the siphon *a*, and rises in the cylinder to the same height at which it stands in the boiler. As the cylinder A is connected by the pipe *c* with the glass tube B, the water will also rise in the latter; and its exact height may thus be at once ascertained by the aid of a graduated scale or other suitable index, which may be marked on the tube B. The upper portion of the tube C is expanded, so as to be similar to a hollow wall. From the latter projects an arm, *h*, to the upper end of which the centre of a horizontal lever, F, is pivoted, one end of which is directly in the continuation of the axis of the cylinder A, while its other end, if pivoted, would pass through the axis of the pipe C or tube B. The latter end is bifurcated, and holds the continued, would pass through the axis of the pipe C or tube B. The latter end is bifurcated, and holds the bell, *i*, of a steam-whistle, and also, by means of a stem, *r*, in the bell, the valve, *j*, of the same, as is clearly shown in fig. 1. The valve *j* closes the cup-shaped upper end and opening *k* of the tube C. The opposite end of the bar F is pivoted to the upper end of a rod, *l*, which passes through the centre of the upper head of the cylinder A, and which is guided in a packing-box, *m*, of suitable length for steadyng the movements of the said rod *l*. From the lower end of the rod *l* is suspended, by means of a chain, *n*, a float, G, which is to swim on the water in the cylinder. A spiral spring, *o*, between a cap, *p*, on top of cylinder and a sliding shoulder on the bar *l*, keeps the rod *l* up, and thereby the valve *j* closed, as long as the weight G is afloat.

As soon as the water in the cylinder A falls so deep that the weight will no more be supported by it, the latter will pull the rod *l* down, and with it that end of the lever F which is above the cylinder A. The valve *j* will thereby be raised, and the steam which was held in the bell portion of the tube C escapes through the opening in the cup *k*. It will then strike the lower edge of the bell *i*, and will thereby whistle and sound the alarm, and notify the attendants that the boiler ought to be refilled.

The spring *o* should be strong enough to keep the whistle closed while the weight G is afloat.

Having thus described my invention, what I claim as new, and desire to secure by Letters Patent, is—

1. The tube E, in combination with the tube B, whereby the cold air is prevented from striking the tube B while hot water is in the latter, substantially as described for the purpose specified.

2. The lever F, pivoted to the arm *h* of the globe C, sliding rod *l*, to which the float G is secured by the chain *n*, packing-tube *m*, and spring *o*, all arranged and operating as herein set forth, for the purpose specified.

R. A. FILKINS.
